MANICURE SET

Anthony J. Miller, Freeman, S. Dak.

Application May 2, 1947, Serial No. 745,376

1 Claim. (Cl. 132—75.5)

1

This invention relates generally to the class of toilet articles and is directed particularly to improvements in manicuring devices, more especially a device for use in pedal manicure.

A principal object of the present invention is to provide a manicure device of the character stated which combines in one compact unit all of the articles necessary to a complete pedicure or treatment of the feet.

Another object of the invention is to provide a device of the character stated wherein there is combined with a body forming a handle and having associated therewith a pair of files, a cutter in the form of a clipper or snipper, for trimming the nails, and a removable cap being provided which screws onto the end of the handle forming body to enclose the clipper to shield the same when it is not in use.

Another object of the invention is to provide a combination implement of the character stated which has in addition to the clipper attached to one end of the handle forming body, a scraper having a head resembling a safety razor, with opposite relatively sharp edges which may be used safely for the removal of dead skin and calluses.

The invention will be best understood from a consideration of the following detailed description taken in connection with the accompanying drawing forming a part of the specification, with the understanding, however, that the invention is not to be understood as limited to the exact details of construction shown and described since obvious modifications will occur to a person skilled in the art.

In the drawing:

Figure 1 is a view partly in side elevation and partly in section showing an implement constructed in accordance with the present invention, the scraper being removed.

Figure 2 is a view in side elevation of the implement showing the clipper cap removed and showing the clipper in top plan, the scraper being removed.

Figure 3 is a fragmentary view partly in section showing a portion of the handle body and the scraper attached thereto.

Figure 4 is a sectional view, on an enlarged scale, taken substantially on the line 4—4 of Figure 2.

Figure 5 is a view in side elevation of the clipper unit per se.

Figure 6 is a transverse section taken substantially upon the line 6—6 of Figure 1.

Referring now more particularly to the drawing the numeral 10 generally designates the body

of the present implement, which body performs the double function of providing a handle and a carrier or support for a pair of files.

The body 10 is preferably formed of solid material of suitable character and preferably, though not necessarily, is of circular cross section as shown in Figure 6.

When made in this cross sectional form the body 10 has fixed to opposite sides the relatively long file bodies 13 and 14 respectively. These bodies are of the same transverse curvature as the handle body 10 to which they are secured as shown in Figure 6.

At one end the handle body 10 is provided with the reduced stem 15 which is screw threaded as indicated at 16 to receive and be connected with the open end of a long tubular cap 17. This cap at its open end is interiorly screw threaded as indicated at 18 for threaded connection with the stem 15 while the opposite end of the cap is closed as shown.

Formed axially in the stem 15 and the adjacent end of the body 10 is a threaded socket or bore 18. This is provided to receive a threaded stem, as hereinafter described, of nail clippers which are generally designated 19.

The clippers comprise a circular base portion 20 from one end of which extend the two resilient blades 21 and 22. These blades are secured firmly together at their inner ends and are biased slightly to separate at their outer ends. The outer ends of the blades 21 and 22 are of substantial width as shown in Figure 2 and each terminates in the curved cutting edge portion 23.

Opposite sides of one of the blades, here shown as the blade 22, have formed integral therewith the spaced parallel ears 24 which extend across the side edges of the adjacent blade and between these ears is pivotally engaged by means of the pins 25, the laterally turned or angled foot portion 26 of the lever 27. The rear end of this lever is cut off or tapered as indicated at 28 for the purpose about to be described.

The base portion 20 of the cutters is screw threaded to receive the locking nut 29 by means of which the lever 27 is secured in lowered or down position. This locking nut 29 has the annular groove 30 in the forward face thereof to receive the tapered end 28 of the lever 27. It will be readily apparent that when the locking nut 29 is threaded back and the lever 27 pushed down, by then threading the nut 29 forwardly the tapered end 28 will be engaged in the circular groove 30 so that the lever will be held in place. The

cutting edges 23 will thus be secured in closed relation.

The base portion 20 includes as a portion thereof the relatively large disk 31 and extending axially from this disk 31 upon the opposite side from the base portion 20, is the threaded stem 32 which is designed to be threaded into the socket 18. When fully threaded into the socket the disk 31 will come to rest against the outer end of the stud 15 as shown in Figures 1 and 2.

When the clipper is secured to the end of the base portion 10 the cap 17 can be placed thereover and coupled with the threaded portion 16 of the stud 15 thus completely enclosing and protecting the clippers.

At the opposite end of the base portion 10 there is formed the axial threaded socket or bore 33. This socket is provided to receive the threaded stem portion 34 which forms an integral part of a scraper head which is generally designated 35.

The scraper head 35 is of generally arcuate form and the opposite edges 36 are sharpened to facilitate the cutting away or scraping away of calluses and dead flesh.

The stem 34 includes as an integral part thereof the collar 37 which limits the inward threading of the stem 34 into the socket and provides a solid support against the end of the base portion 10 for the scraper.

In order to protect the cutting or scraping edges 36 of the callus removing head, there is provided the arcuate resilient cover or cap, which may be made of any suitable material such as metal, a suitable resin or the like, generally designated 38. This cap or cover 38 has its opposite ends or transverse edges turned back or turned inwardly forming the narrow flanges 39, which flanges form with the adjacent underside of the cover body, the channels or grooves 40 in each of which an edge 36 of the scraper is slidably engaged. In this manner the flanges 39 not only

function to protect or cover the edges of the scraper but they also function to maintain the cover in position on the scraper head.

From the foregoing it will be readily apparent that there is provided in the present invention a novel, compact and serviceable tool or instrument for use in manicure operations, more particularly for manicuring the toenails and generally treating the feet.

10 I claim:

A manicure implement of the character stated comprising a relatively long handle body having a threaded axial bore in one end, a cutting implement comprising a pair of resilient blades, said blades being attached to a body of circular form, the body being exteriorly screw threaded, a stem forming an integral part of the body and adapted to engage in said socket, said cutting implement including a lever pivotally coupled with one blade and adapted to apply pressure to the other blade to move the same together into operating relation, said lever being adapted to be moved into substantially parallel relation with the blades, and a threaded nut mounted upon said body and adapted when moved in one direction to engage and secure said lever in the said substantially parallel relation with the blades.
